UNITED STATES PATENT OFFICE

2,540,001

DOUBLE SEAMER

Ed Laxo, Oakland, Calif., assignor to Atlas Imperial Diesel Engine Co., Oakland, Calif., a corporation of Delaware

Application October 18, 1948, Serial No. 55,130

1 Claim. (Cl. 113—23)

1

This invention relates to a double seamer for forming seams to join together can ends and can bodies.

Can end seamers generally in use today comprise a pair of spaced, rotatable turrets, one of which, usually the lower turret, is provided with chucks which rotate with the turret and also reciprocate to bring the can bodies and superimposed ends against the chucks of the upper turret. The upper turret is provided with two driven cams, one of which operates a first seaming roll and the other a second seaming roll. Such design requires a considerable amount of gearing for driving.

It is an object of the present invention to provide an improved form of double seamer for performing seaming operations on can ends.

It is a further object of the invention to provide a can end seamer which is operable to form the seams on can ends without employing a driven cam.

These and other objects of the invention will be apparent from the ensuing description and the appended claim.

One form which the invention may assume is exemplified in the following description and illustrated by way of example in the accompanying drawings, in which:

Fig. 1 is a vertical section through the double seamer of the invention.

Fig. 2 is a horizontal section taken along the line 2—2 of Fig. 1, showing the seaming cam in top-plan view, and also showing the followers and seaming rolls for performing the first and second seaming operations.

Fig. 3 is a view on a larger scale, partly in side elevation and partly in section, showing a seaming unit.

Fig. 4 is a section taken along the line 4—4 of Fig. 3, showing the means of adjusting the seaming rolls.

Fig. 5 is a top-plan view of the seaming unit of Fig. 3.

Referring now to the drawings, and more particularly to Fig. 1, the double seamer is generally designated as 10 and it comprises a frame 11 within which are disposed a gear train consisting of a bevel pinion 12, a bevel gear 13 and gears 14 and 15, the bevel pinion 12 being secured to the main drive shaft 16 and the gear 15 being secured to a shaft 17. The shaft 17 is journaled in bearings 18 and 19 which are housed in a stationary sleeve 20, and it also extends downwardly below the sleeve 20 and through a rotatable sleeve 25. In the lower part of the machine as shown

2

in Fig. 1, there is provided the usual lower turret 26 having reciprocating chucks 27. The shaft 17 operates the lower turret 26 and the reciprocating chucks 27 in known manner.

There is also shown an upper turret or seaming head 28, and the sleeve 25 is keyed at 29 to the hub 30 of upper turret 28. Chucks 31 of conventional construction are carried by the turret 28, and each chuck is rotated relatively to the

turret by means of a gear 32 engaging a gear 33 which is keyed at 34 to the shaft 17. The turret 28 is suspended by means of rollers 40 riding in a circular groove 41 formed in the hub 42 of a stationary cam 43, which is described in more detail hereinafter. A can knockout mechanism of conventional design is also provided, including rollers 44 riding in a cam groove 45 formed in the hub 42, such rollers actuating knockout rods 46 which are urged upwardly by coil springs 47.

The seaming cam 43 is slidable on the sleeve 20 to vary its height and, correspondingly, the height of the upper turret 28, for the purpose of accommodating can bodies of different height. The cam 43 is adjustable by means of a rod 48

extending through the frame 11 and a lug 49 bolted to the cam. As shown, the rod 48 is secured to the frame 11 by means of a set screw 50, and the cam 43 is clamped in adjusted position by means of a clamping screw 51.

The seaming cam 43 has a groove 55 formed therein near its periphery and on its underside. The groove 55 has an outer face 56 forming a first cam track and an inner face 57 forming a second cam track. As shown in Fig. 2, the first

cam track 56 is provided with a low dwell 58, a high dwell 59 and shoulders 60 and 61, and the inner or second cam track 57 is formed with a similar but angularly displaced low dwell 62, and a corresponding high dwell 63 and shoulders 64 and 65.

As shown in Fig. 3, the turret 28 is formed of units 66, each comprising a chuck 31 and first and second seaming rolls 67 and 68, respectively. The rolls 67 and 68 are of conventional design and function, the first roll serving to perform the first bending and interlocking operation on the can end and can body end flange, and the second roll serving to finish the seaming operation. The first seaming roll 67 is rotatable in a crank 69, which is actuated by a crank shaft 70 rotatable in a housing 75. Similarly, the second seaming roll 68 is rotatable in a crank 76 which is actuated by a crank shaft 77 rotatable in the housing 75. Crank shaft 70 is rotatable by a cam follower roller 78 and a lever or crank 80,

and the other crank shaft 77 is similarly rotatable by means of a cam follower roller 81 and lever or crank 82. The roller 79 is urged against the first cam track 56 by a coil spring 83, and the other roller 81 is urged against the second cam track 57 by means of a coil spring 84. Set screws 83a and 84a are provided for adjusting the compression on springs 83 and 84.

Each crank shaft 70 or 77 and its associated seaming roll 67 or 68 is adjustable angularly by means of a threaded collar 85 keyed to the crank shaft at 86 and rotatable by means of a screw 87 having a square socket 88 adapted to engage a wrench 89 (see Fig. 4).

In operation, can bodies 95 having can ends 96 disposed thereon at their upper ends are supplied to the double seamer manually or by any other suitable means. For example, the can bodies and ends may be fed to the double seamer by means of an end feed and body feed described in my copending application Serial No. 55,128, filed October 18, 1943, entitled "Can end feed mechanism." As the shaft 17 is caused to rotate, the lower turret 26 will, of course, rotate and its chucks 27 will reciprocate, so as to elevate a can body and end against an upper chuck 31. Meanwhile, the upper turret 28 is constantly rotating and each chuck 31 is caused to rotate about its own axis. As indicated in Fig. 2, can bodies and can ends enter the double seamer at the position indicated as A and leave at the position indicated as B. It will be seen that, shortly after a can body and can end leave the position A, the first cam follower roller 79 will ride up the shoulder 60 onto the high dwell 59 of the first or outer cam track 56. This will cause rotation of the crank shaft 70 in a clockwise direction, as viewed in Fig. 5, thus bringing the first operation seaming roll 67 against the can body and can end, causing the first step in the formation of an end seam. When the can body and can end reach the shoulder 64, the roller 80 will ride down the said shoulder onto the low dwell 58. Shortly thereafter the second cam follower roller 81 will ride up the shoulder 64 onto the high dwell 63 of the second or inner cam track 57, thus causing rotation of the crank shaft 77 and the second operation seaming roll 68 in a counter-clockwise direction, as viewed in Fig. 5. This will cause the second operation seaming roll 68 to move inwardly toward the can body and can end, thus performing the second and final seaming operation. Finally, when the can body and can end reach the shoulder 65 of the inner or first cam track 57, the roller 81 will ride down the said shoulder onto low dwell 62, and the can body and can end will be ejected (by the knockout rod 46) and removed by any suitable mechanism (not shown) at the position B.

It will thus be apparent that a can end double seamer has been provided which is capable of operation at very high speed and in which the first and second operation seaming rolls are actuated by the first and second, stationary cam track. Gearing intermediate the shaft 17 and the seaming rolls is eliminated, and the machine is further simplified by the provision of a single groove to provide two cam tracks. Also, provision is made for adjusting the angular position of the seaming rolls, and the means of adjusting the height of the upper turret is simplified.

While I have shown the preferred form of my invention, it is to be understood that various changes may be made in its construction by those skilled in the art without departing from the spirit of the invention as defined in the appended claim.

Having thus described my invention, what I claim and desire to secure by Letters Patent is:

In a double seamer the combination with a rotatable turret having a plurality of pairs of successively acting seaming rolls, and an actuating shaft, crank and cam follower for each roll, all of said followers being disposed in horizontal alignment, of a relatively stationary cam for successively actuating each roll of each pair, said cam having a single cam groove within which all of said cam followers are located and moved upon relative rotation of the turret with respect to the cam, said groove being formed by parallel facing side walls in registering horizontal alignment, said walls each defining a separate and distinct cam path and being spaced a distance apart greater than the width of the cam followers, whereby a follower in contact with one wall will be out of contact with the opposite wall, and means continuously urging one follower of each pair in contact with one wall and means continuously urging the other follower of each pair in contact with the opposite wall.

ED LAXO.
